CLAIM

I claim the ornamental design for a cupcake stand ambient light, as shown and described.

DESCRIPTION

FIG. 1 is a perspective view of a cupcake stand ambient light showing my new design;

FIG. 2 is a top view of the cupcake stand ambient light of FIG. 1;

FIG. 3 is a bottom view of the cupcake stand ambient light of FIG. 1;

FIG. 4 is a front view of the cupcake stand ambient light of FIG. 1;

FIG. 5 is a back view of the cupcake stand ambient light of FIG. 1;

FIG. 6 is a left side of the cupcake stand ambient light of FIG. 1;

FIG. 7 is right side view of the cupcake stand ambient light of FIG. 1; and,

FIG. 8 is another perspective view of the cupcake stand ambient light of FIG. 1.

The broken lines on the drawings depict environment only and form no part of the claimed design.

1 Claim, 6 Drawing Sheets
